UNITED STATES PATENT OFFICE

HAROLD H. BOYER, OF CANTON, OHIO, ASSIGNOR TO THE HOOVER COMPANY, OF NORTH CANTON, OHIO, A CORPORATION OF OHIO

SUCTION CLEANER

Application filed February 20, 1931. Serial No. 517,213.

The present invention relates to suction cleaners in general and more particularly to new and novel improvements in suction cleaner construction which serve to increase the 5 range of usefulness of the cleaner thru making it accessible to many portions of the surface covering which have usually been considered beyond its reach. More specifically the present invention comprises the provision of a suction cleaner having an extensible cleaning nozzle which can be readily adjusted to one of a plurality of positions relative to the cleaner proper.

In the use of the ordinary suction cleaner 15 many areas of the surface covering positioned under heavy articles of furniture which are not readily movable and which approach the supporting surface in such proximity that the cleaner is not movable thereunder are neglected and are left to a supplementing broom or mop. The ordinary suction cleaner necessarily has a definite height, usually of some eight to ten inches above the supporting surface, thereby resulting in the inclusion of all 25 covering areas under heavy pieces of furniture, which approach the covering within those ranges, in the field outside the cleaner's sphere. Cleaners have been designed with the idea in mind of making the total overall 30 height as small as possible for the express purpose of permitting the cleaner to gain entrance under as many articles of furniture as possible, but it is obvious that there are certain lower limits under which the height 35 of the cleaner cannot be decreased, there being certain essential and necessary parts, and though the cleaner is well designed the height will still be relatively great. In the suction cleaner constructed in accordance with the 40 present invention, means have been provided by which the effective height of the suction cleaner can be decreased to a fraction of its usual amplitude. This effect is accomplished thru the provision of an extensible nozzle 45 which is an integral part of the cleaner and which is so designed that it can be easily adjusted in a horizontal plane relative to the cleaner by the operator. As the height of the nozzle proper above the surface covering is 50 relatively small, as compared to that of the

entire cleaner, it is apparent that for the length of the extended nozzle the cleaner has an effective height no greater than the nozzle height and that the machine can be operated with this portion alone extended under articles of furniture, if necessary. 55

It is an object of the present invention to provide a new and improved suction cleaner. It is another object to provide, in a suction cleaner, new and novel improvements which function to increase the range of usefulness of the cleaner. It is a still further object to provide a permanently carried horizontally extensible nozzle in a suction cleaner. It is a still further object to provide, in a suction 60 cleaner, a permanently incorporated nozzle which is manually adjustable by the operator. It is still another object of the present invention to provide a new and improved suction cleaner construction in which the cleaner nozzle can be adjusted horizontally relative to the remainder of the cleaner. These and other more specific objects will appear upon reading the following specification and claims and considering in connection therewith the attached drawings to which they relate. 65

In the drawings in which a preferred embodiment of the present invention is disclosed and in which the same reference characters refer to like parts in the various views: 70

Fig. 1 is a side view, partially in section, showing a suction cleaner with the present invention embodied therein;

Fig. 2 is a section upon the line 2—2 of Fig. 1;

Fig. 3 is a partial top view showing the front of the cleaner;

Fig. 4 is a rear view of the suction cleaner shown in Fig. 1;

Fig. 5 is a partial section, similar to Fig. 2, showing a modified construction. 80

The suction cleaner constructed in accordance with the present invention, as shown in the drawings, comprises a fan chamber 10 with which are integrally formed, preferably, a downwardly and forwardly extending intake conduit 11 and an exhaust outlet 12. Fan chamber 10 is interiorly connected to the intake conduit 11 thru the inlet or eye 13 and there is preferably provided a detach- 85

able cover plate or section 14, in the conduit 11 at the eye 13 of the fan chamber, which is removably secured in place by means of a spring pressed detent 15 but which may be removed in order that a dusting tool may be connected to the eye 13 of the fan chamber. Motor casing 16 is positioned adjacent the forward side of the fan casing 10 and encloses an unshown driving motor for the fan 17 which is rotatably mounted within the casing 10 upon the extended end of the motor shaft 18. As distinguished from the usual suction cleaner construction the intake conduit 11 extends under and along the length 15 of the motor casing 16 which is itself provided with a suitable contacting base. A dust bag 19 is secured to the exhaust outlet 12 of the fan casing, as in the usual cleaner, and is suspended at its upper end, in a manner which is not shown and which forms no part of the present invention, from the handle 20. This handle is pivotally connected at its lower end to the motor casing 16 and, thru being hollow, provides a conduit for the 25 incoming power lead 21 which, at a lower point, enters the motor casing 16. Handle-position-controlling means are provided at the lower end of the handle comprising an arcuate sector 22 carried by one of the divided arms of the handle. The outer face of sector 22 is provided with suitable seats which are adapted to be contacted by a spring-pressed plunger 23 carried by the motor casing 16 as in the usual suction cleaner 30 construction. The front of the cleaner is movably supported by means of spaced wheels 24, 24 which are carried by brackets 25, 25 which extend downwardly from the motor casing 16 at the sides of the intake 35 conduit 11. The rear of the cleaner, which in the usual suction cleaner would be the front, is supported by a pivoted wheel 26 which is provided with adjusting means 27 whose function it is to raise and lower the 40 wheel for the purpose of pivoting the cleaner about the front supporting wheels as an axis. The suction cleaner nozzle, which is positioned in the usual suction cleaner on a line substantially thru the point occupied by the 45 rear wheel 26 and upon the opposite side of the fan chamber from the motor casing 16 is, in the present instance, carried by the intake conduit 11 and is adapted to contact the surface covering undergoing cleaning at a 50 point forward of the said casing 16, and on the same side of the fan chamber. In the drawings the cleaner nozzle is indicated by the reference character 28 and comprises an elongated channel which is widened at its 55 end forward of the conduit 11 into a downwardly facing opening or mouth, the edges of which are defined by the front and rear nozzle lips 29 and 30. As is perhaps most clearly shown in Figure 1, nozzle 28 is seated 60 within the intake conduit 11 and conforms

to the shape thereof. The nozzle is not rigidly positioned within the conduit but instead is slidably mounted therein and may be adjusted between the position shown in full lines in Figure 1 and the position shown in dotted lines. Means are provided, in the form of a spring-pressed detent 31 carried by the conduit 11, which is adapted to cooperate with spaced recesses or seats 32, 32, etc., in the adjacent side of the nozzle 28 to hold the nozzle in any set position relative to the conduit 11, the unintentional withdrawal of the nozzle from the conduit being prevented by a set screw 37 carried by the upper wall of the conduit which slides in a longitudinal groove 38 formed in the adjacent side of the nozzle. Spaced felt seals 33 and 34 are carried at the forward end of the conduit 11 and the rearward end of the nozzle 28, respectively, which function to prevent leakage of air into the fan chamber 10, in response to the reduced pressure created therein by the rotating fan 17, thru any other means than the mouth of the nozzle 28 as defined by the lips 29 and 30. The usual nozzle position 95 relative to the cleaner is that shown in full lines in Figure 1 and is that position in which a shoulder 35 carried by the nozzle 28 contacts the end of the conduit 11. The nozzle may be withdrawn from the conduit 11 as far as the nozzle length will permit and as limited by the screw 37 in the longitudinal groove 38.

In Figure 5 a slightly modified embodiment of the present invention is disclosed in which the nozzle-positioning means comprising the spring pressed lever or detent 31 of the first described modification and its cooperating seats 32, 32 have been replaced by a manually rotatable screw member 36, carried by the conduit 11, which is adapted to be tightened in its seat in the conduit to contact the adjacent side of the nozzle 28 to clamp the nozzle in place.

The operation of the suction cleaner constructed in accordance with the present invention is extremely simple. In the usual operation of the machine the nozzle will be positioned as shown in full lines in Figure 1 and the machine will be operated as any other machine. Upon the necessity arising for cleaning under an article of furniture under which the cleaner proper will not pass it is only necessary for the operator to pull the nozzle 28 forwardly from the remainder of the cleaner, resulting in its sliding in the conduit 11, to some position, the extent of which will be determined by the distance under the article of furniture to which the nozzle must reach. The nozzle will be retained in the set position by means of the spring-pressed detent 31, or, if the adjustment means were constructed in accordance with the second embodiment, it would be necessary for the operator to first loosen the 125

adjusting screw 36 to permit the withdrawal of the enclosed nozzle 28 and then to tighten it after the nozzle had been adjusted to the desired position.

5 I claim:

- 6 1. A suction cleaner comprising a suction-creating unit, a suction nozzle having an intake opening and movably carried by said unit, means movably supporting said unit and said nozzle with said intake opening addressing the surface covering undergoing cleaning, characterized by the fact that said nozzle is adjustable horizontally relative to said suction-creating unit.
- 10 2. A suction cleaner comprising a suction-creating unit, a suction nozzle having an intake opening and slidably carried by said unit, means movably supporting said unit and said nozzle with said intake opening addressing the surface covering undergoing cleaning.
- 15 3. A suction cleaner comprising a suction-creating unit, a suction nozzle having an intake opening and slidably carried by said unit, means movably supporting said unit and said nozzle with said intake opening addressing the surface covering undergoing cleaning, and means carried by said unit to maintain said nozzle in one of a plurality of
- 20 30 positions.
- 35 4. A suction cleaner comprising a suction-creating unit having a horizontal elongated intake conduit, a suction nozzle having an intake opening and slidably positioned in said conduit and adapted to assume one of a plurality of horizontal positions for the purpose of spacing said intake opening from said unit, and means movably supporting said unit and nozzle with said intake opening addressing the covering undergoing cleaning.
- 40

Signed at North Canton, in the county of Stark and State of Ohio, this 16th day of February, A. D. 1931.

HAROLD H. BOYER.
